UNITED STATES PATENT OFFICE.

WILLIAM ABRAMS, OF CHICAGO, ILLINOIS.

DESIGN FOR A PLATE.

46,106.

Specification for Design.

Patented July 21, 1914.

Application filed May 4, 1914. Serial No. 836,376. Term of patent 3½ years.

To all whom it may concern:

Be it known that I, WILLIAM ABRAMS, a citizen of the United States, residing at Chicago, in the county of Cook and State of Illinois, have invented a new, original, and ornamental Design for Plates, of which the following is a specification, reference being had to the accompanying drawing, forming a part thereof.

The drawing illustrates a plan view of the plate showing my new design.

I claim—

The ornamental design for a plate as shown.

WILLIAM ABRAMS.

Witnesses:

F. P. VEITH,
Wm. A. BLAIR.
